AUTOMOBILE ARM REST COVER

Walter E. Jeckell, Huntington Park, Calif.
Application May 4, 1954, Serial No. 30,318

Term of patent 3½ years
(Cl. D14—6)

FIG. 1

FIG. 2

FIG. 3

FIG. 4

FIG. 5

Fig. 1 is a top elevational view of an automobile arm rest cover embodying my new design;

Fig. 2 is a front elevational view of the same;

Fig. 3 is a rear elevational view of the same;

Fig. 4 is an end view of the same.

Fig. 5 is an end view taken from the opposite end.

I claim:

The ornamental design for an automobile arm rest cover, substantially as shown.
